UNITED STATES PATENT OFFICE

CONRAD JOBST, OF TOLEDO, OHIO, ASSIGNOR TO THE TOLEDO AUTOMATIC BRUSH MACHINE COMPANY, OF TOLEDO, OHIO, A CORPORATION OF OHIO

BRUSH MACHINE

Application filed September 2, 1930. Serial No. 479,372.

The invention relates to brush machines and more particularly to machines for forming brushes having closely spaced bristle tufts mounted in thin backs such for instance as tooth brushes. It is the object of the invention to automatically complete the brush after a single setting of the back or handle. This necessitates the drilling of the holes for receiving the tufts, the setting of the tufts therein and the trimming of the bristles to any desired contour, both longitudinally and transversely of the back, all of said operations being performed automatically in proper sequence.

In the development of the art machines have been devised in which the boring of one brush back and the setting of tufts in a previously bored back are simultaneously accomplished. Machines of this type when used for manufacturing brushes with celluloid backs were limited in speed by the length of the time interval required for boring each hole in such material. In further development of the art, advance in the speed of forming and setting the tufts rendered it desirable to segregate the boring and tuft setting operations, inasmuch as the speed of the latter must necessarily be limited by that of the former. However, with improvement in materials for drills it has become possible to increase the speed of the drilling operation so as to equal that of the tuft setting mechanism, but to successfully operate at such high rate of speed requires extreme accuracy in registration.

The present invention comprises essentially a construction of work holding and feeding unit with which brush backs may be easily engaged and by which these backs are successively presented to the drilling, the tuft setting and the trimming units and with such extreme accuracy of registration as to permit of operating at a very high rate of speed. The construction is also one which is adapted for use with brush backs of various shapes and designs such as either plain or curved faces and with the tufts set either in straight parallel rows or otherwise distributed. With every adjustment of this kind there will be the same accuracy of registration so that the

tuft setting nozzle will always deliver the tuft into the hole previously bored in the back.

The construction of each of the drilling, tuft setting and trimming mechanisms per se is not essential to the present invention which is adapted for use with any suitable combination of such mechanisms arranged in operative relation to my improved work holding and feeding unit, and the invention therefore consists in the novel construction, arrangement and combination of parts constituting this unit as hereinafter set forth.

In the drawings:

Figure 1 is a vertical central section through the machine;

Figure 1a is a sectional detailed view of a portion of Figure 1;

Figure 2 is a plan view partly in section;

Figure 3 is an end elevation;

Figure 4 is a vertical section on line 4-4 of Figure 2;

Figure 4a is an elevation viewed at right angles to Figure 4 showing the engagement of the roller with the stepped cam;

Figure 5 is an elevation showing means for engaging and releasing the brush back clamps;

Figure 6 is an elevation partly in section of the means controlling the rotative movement of the drum;

Figure 7 is a sectional elevation at right angles to Figure 6;

Figure 8 is a vertical section through the controlling valves, and

Figure 9 is an end elevation thereof.

Generally described, my improved machine comprises a rotary and axially adjustable drum having secured to the periphery thereof a series of brush back holders together with clamping and releasing means permitting of the introduction and removal of the work. This drum 1 is rotatively mounted on an inner hollow frame member 2 which has at its upper end a recess 3 with the ball bearings 4 and 5 located therein. The drum 1 has a top head 6 with a depending hub 7 for engaging said ball bearings 4 and 5. Intermediate the drum 1 and the frame 2 is an annular frame 8 which has dis-

tributed thereabout a plurality of vertical guideways 9 registering with corresponding vertical guideways 10 on the member 2 and with balls 11 in a cage or retainer 12 therebetween. This arrangement permits of a comparatively frictionless vertical movement of the frame 2 and drum 1 thereon with respect to the frame 8 and a frictionless rotary movement of the drum 1 with respect to the frames 2 and 8.

The frame 8 has a shelf portion 8^a which is horizontally adjustably mounted on a member 13 which is in fixed relation to the drilling, tuft setting and trimming units (not shown). To permit of such adjustment the frame 8 and member 13 are provided with registering raceways 14 and 15 with balls 16 therebetween, so that the movement is comparatively frictionless. Journaled upon the frame 8 and between the same and the drum 1 is a rotary cam carrier 17 which has secured thereto an annular bevel gear 18 intermeshing with a bevel pinion 19 on a shaft 20. This shaft is driven through the medium of change gears 21 from a parallel shaft 22 which in turn is driven through bevel gear wheels 23 from a power shaft 24. A vertical shaft 25 is also driven from this power shaft through the bevel gear wheel 26 to which it is splined so as to permit of axial movement in relation thereto. The lower end of the shaft 25 is coupled by bevel gear wheels 27 with a horizontal shaft 28 mounted on a lateral extension 29 of the frame 2. A shaft 30 is axially aligned with the shaft 28 and between these shafts is a friction coupling 31 through which a limited torque is transmitted from the shaft 28 to the shaft 30. The shaft 30 is connected by bevel gear wheels 31 with a vertical shaft 32 which extends upward between the frame 2 and the frame 8 and has at its upper end a pinion 33 in mesh with a ring gear 34 secured to the under side of the head 6 of the drum 1. The arrangement is such that the rotary motion of the power shaft 24 is communicated through the shafts 25, 28, 30 and 32, pinion 33 and ring gear 34 to impart a rotary motion to the drum 1 which, however, is not positive as the friction clutch 31 will permit of arresting movement of the drum as will be hereinafter explained. The power shaft 24 also drives the cam carrier 17 through the medium of the bevel gears 23, shaft 22, change gears 21, shaft 20, bevel pinion 19 and ring gear 18, the rotation of said cam carrier being properly timed by the change gears to correspond to the particular character of work to be performed.

The cam carrier 17 has mounted on its upper end a stepped cam 35 engaging a roller 36 mounted on a radial extension 37 of the frame 2 which extension passes through a slot 38 in the frame 8. The steps on this cam are in ascending and descending series

corresponding to the several rows of tufts and the number of individual tufts in each row. If the number of rows in each brush back is odd, then the cam is provided with at least double that number of ascending and descending portions, so that after a complete cycle the starting point will be in the same position.

In addition to the stepped cam 35 the cam carrier 17 has mounted thereon a series of peripheral cams for performing various functions. One of these cams 36^a is adapted to cooperate with a roller bearing 37^a on an arm 38^a extending from the stationary frame 13. The purpose of this cam is to move the frame 8 and all of the parts mounted thereon in relation to the fixed frame and the drilling, tuft setting and trimming units, in case the brush back has a curved instead of a plain face. On the other hand, where the brush back is flat the cam 36 may be concentric with the axis of the drum so as to impart no movement to the frame 8 relative to the frame 13. A rod 39 and spring 40 forms a yieldable connection between the frame 8 and arm 38^a, thereby holding the cam 36 constantly bearing against the roller 37.

The stepped cam 35 in cooperation with the roller 36 will intermittently raise and lower the frame 2 but will have no effect upon rotary movement of the drum 1. This rotary movement as previously described is communicated to the drum by the pinion 33 engaging the ring gear 34, but the driving is not positive due to the friction coupling 31 between the shafts 28 and 30. To hold the drum from rotation against this yielding drive it is provided near its lower end with an exchangeable ring 41 having an outwardly extending flange 42 provided with spaced notches 43, corresponding to the spacing of the several rows of tufts in each brush and the spacing between adjacent brushes. This ring 41 may be exchanged for another whenever the number of rows of tufts in the brushes operated upon is changed. The notches 43 are successively engaged by a vertical V-shaped guide member 44 which is of a length greater than the vertical movement of the drum and is intermittently radially withdrawn to permit the rotation of said drum under the actuation of its friction drive. Such radial withdrawal is timed by the operation of trip members 45 suitably rotatively spaced around the cam carrier 17 and cooperating with mechanism constructed as follows:

The guide 44 is mounted upon a bifurcated arm 46 which is pivotally connected by the shaft 47 with a bifurcated lever arm 48 fulcrumed upon a vertical pivot shaft or post 49 mounted on the shelf 8^a. On this same pivot shaft 49 is fulcrumed an arm 50 which extends into proximity to the arm 46 and bears against an adjustable stop 51 on said

arm. A spring 52 engaging a bell crank arm 53 connected to the arm 46 and anchored to a post 52^a serves to yieldably hold the guide 44 in engagement with one of the notches 43 and a spring 54 yieldably holds the arm 50 in engagement with the stop 51. The arm 50 is provided with a radially inwardly projecting inclined face 55 which is adapted to be engaged by an inclined face 56 on the trip member 45. Thus during the rotation of the cam carrier 17 the inclined face 56 on the trip member 45 periodically comes into contact with the inclined face 55 on the arm 50, instantaneously rocking said arm and the arm 46 and withdrawing the guide 44 from the notch 43. The arm 50 is almost instantly released by the passage of the member 45 beyond the member 55 so that the guide 44 will again be moved inward by the tension of the spring 52. However, in this brief interval sufficient movement will be imparted to the drum 1 to pass from one notch 43 into registration with another.

As just described, the guide 44 will hold the drum from rotation during its upward or downward step by step movement actuated by the stepped cam 35. At each of the steps the drilling and tuft setting mechanisms will operate to respectively drill a hole in a brush back and to set a tuft in the corresponding hole of a previously bored back. Also by properly positioning the trips 45 the guide 44 is withdrawn at the completion of each row of holes and tufts to be engaged with the next notch 43 in which position the drilling and tuft setting mechanisms successively operate upon another row. Thus the two rows will be exactly parallel to each other and consequently the tufts in each row will be spaced a uniform distance apart. It is, however, frequently desirable to have the rows of tufts non-parallel, which I accomplish in the following manner.

It has been stated that the arm 46 is pivotally connected to a lever 48 which is fulcrumed upon the pivot shaft 49. At the opposite end of this lever 48 is a roller 57 which bears against a cam 58 on the cam carrier 17. The cam 58 is so fashioned as to gradually rock the lever 48 on its fulcrum 49 and in so doing move the pivot 47 to which the arm 46 is attached. This will change the position of the guide 44 so that the drum 1 instead of being held from rotation is permitted to slightly rotate and thus to change the path of the brush backs operated upon from an exact vertical line to an inclined or curved line. This path can be exactly predetermined by properly fashioning the cam 58 so that any desired inclination or curvature can be given to the rows without the necessity of changing the guide 44.

In the manufacture of brush backs from materials such as celluloid it has been found impractical to hold these backs to exact di-

mensions, particularly as to thickness. Therefore, if the brush back is positioned in its holder by the back side, the front side which is operated upon by the drilling and tuft setting mechanisms may vary in position according to the thickness of the individual backs. To avoid the inaccuracy which would result from this variation, I have devised a construction where each back is positioned in relation to its front or bored and tufted face, instead of being located by the rear face. It is however, very essential that the back should be rigidly held during the drilling and tufting operations, particularly against the impact of the driver which sets the tufts so that the mounting in the holder can not be of a yielding nature. This I have accomplished by a holder of the following construction:

Secured to the periphery of the drum 1 are the channeled holders 59 which are of a width somewhat greater than the width of the brush back and which have at their outer ends flanges 60 which slightly overlap the back. In each of these channels is a floating wedge member 61 which has at its lower end a laterally extending finger 62 extending beneath the channel portion of the member 59 and between the same and an annular flange 63, thereby holding said wedge member from disengagement but permitting it to move radially in the channel. 64 is a cooperating wedge member which is oppositely tapered and is located in rear of the wedge member 61. The upper end of the wedge 64 has a radially inwardly extending flange 65 which at certain points in the movement of the drum 1 will come into registration with an actuating member. As shown in Figure 2 there are two of these actuating members 66 and 67 located adjacent to different points in the orbit of the drum and respectively operating to press the wedge member 64 downward for clamping the brush back and to lift said wedge member to release the back. As specifically shown, the actuators 66 and 67 are pneumatically operated and receive the operating air through conduits 68 which connect with conduits 69 and 70 concentrically arranged and passing through the center of the drum 1. The lower ends of the conduits 69 and 70 are connected to a valve housing 71 by flexible conduits 71^a located on the frame 8 in a position to be in operative relation to a pair of cams 72 and 73 on the cam carrier 17. The arrangement is such that during the revolution of the cam carrier 17 the cams 72 and 73 will at certain points actuate the valves in the housing 71 so as to admit or exhaust air from the pneumatic actuators 66 and 67. This will cause the depression of the wedge member 64 by one of these actuators and the lifting and withdrawal of said wedge member by the other of said actuators. Thus assum-

ing that the attendant has inserted a brush back into the holder 59 between the floating wedge 61 and the flanges 60 it will be temporarily held in this position by a light 5 spring 72'. When in the rotation of the drum the flange 65 registers with the operator 66 the cam 72 will simultaneously actuate valves in the valve casing 71 so as to cause said actuator to press the wedge 64 downward 10 moving outward the floating wedge 61 and tightly clamping the brush back against the flange 60. The angle of the wedges is such as to be within the angle of friction, so that when once clamped the wedges remain in this 15 position until again actuated for releasing. The contacting surfaces are also non-parallel, as for instance by convexing the surface of the member 61, so that the point of bearing is intermediate the ends. Thus the surface 20 of the member 61 which bears against the brush back will automatically adjust itself angularly to distribute the pressure. The release of the clamp is accomplished by the operator 67 at the time in the rotation of 25 the drum when the flange 65 comes into registration therewith.

The pneumatic motors and the actuators 30 66 and 67 may be of any suitable construction but as shown comprise a piston 73' in a cylinder 74 normally held in raised position by a light spring 75. A plunger 76 is held in guides 77 to extend parallel to the piston and cylinder and is provided with an inwardly 35 extending lug 78 for engaging the piston and an outwardly extending lug 79 for engaging the flange 65 of the wedge 64. The actuators 66 and 67 are substantially the same in construction but with their cylinders and pistons reversed and with the lug 79 of the actuator 66 above the flange 65 of the wedge and the lug 79 of the actuator 67 beneath the flange 65. These actuators may be supported 40 on an arm or plate 80 which extends radially from the outer tubular member 80' forming 45 the conduit 70.

The valves in the casing 71 may be of any suitable construction but as shown two pairs of valves arranged one above the other, each comprising a valve member 81 actuated by a 50 stem 82 and a valve 83 having a tubular stem 84 sleeved on the stem 82. The cams 72 and 73 on the carrier 17 directly engage pivoted rock arms 85 and 86 which are arranged to respectively engage the plunger 82 and the tubular plunger 84. In this way each 55 of the valves 83 and 81 can be independently actuated and timed and the arrangement is such that pressure air is admitted to the cylinder by one and exhausted by the other.

60 On the left hand side of Figure 1 a holder 59a is shown which is the same as the holder 59 but longitudinally curved instead of being straight. This same curvature is in the flanges 60 and floating wedge 61 so that a longitudinally curved brush back may be insert-

ed and held therein. It is to be understood that the construction shown at 59a is an alternative for the construction of 59, the two not being used on the drum at the same time.

70

Operation

In the operation of the machine it will be understood that the drilling mechanism, tuft setting mechanism and trimming mechanism are arranged in positions about the drum 1 to be in operative relation to the brush backs in the holders 59 between the points of clamping by the operator 66 and releasing by the operator 67. It will also be understood that these several mechanisms are properly timed in relation to each other and to the drum actuating mechanism so as to perform their functions simultaneously and during the interval in which the drum 1 is stationary and between actuations thereof rotatively and axially. As these mechanisms perform no part of the present invention, it is not necessary to either illustrate or further describe the same.

75

The cams on the carrier 17 having been properly selected with reference to the particular brushes to be formed and mounted on said carrier, and the change gears having also been properly selected, the machine is ready for operation. Motion derived from the shaft 24 will be simultaneously transmitted to the friction drive for rotating the drum 1 and to the cam carrier 17. The drum 1 will, however, be held from rotation by the engagement of the guide 44 with one of the notches 43 excepting during the periodic operation of the trip 45. This disengages the guide 44 and as the friction coupling 31 is in constant rotation it would quickly overcome the inertia of the drum and impart rotary motion to the same. However, the interval in which the guide 44 is withdrawn is so brief that it will re-engage the next succeeding notch 43 and will arrest further movement of the drum. In each engagement 100 between the guide 44 and a particular notch 43 the stepped cam 35 will successively raise or lower the frame 2 and the drum 1 mounted thereon and at each step a drilling and tuft setting operation will be performed. The exact location of each tuft is determined by the combined action of the guide 44 in cooperation with the notch 43 and by the cam 58 in cooperation with the lever 48. Inasmuch, however, as the controlling cams are in the same 105 position relative to the cooperating mechanism when the tufts are being set as when the holes are being drilled, the registration will be exact and therefore a high speed of operation is possible.

80

110 The exact location of each tuft is determined by the combined action of the guide 44 in cooperation with the notch 43 and by the cam 58 in cooperation with the lever 48. Inasmuch, however, as the controlling cams are in the same position relative to the cooperating mechanism when the tufts are being set as when the holes are being drilled, the registration will be exact and therefore a high speed of operation is possible.

115

120 For feeding the machine, the attendant successively places the brush backs in the holders 59 in advance of the point where the operator 66 tightens the wedges and to which position the floating wedge 61 is freely mov-

125

130

able. The same attendant can remove the completed brushes from a point beyond or after the operation of the operator 67 where the wedge 64 has been again released. Intermediate these two points the back is held rigid and has its front face exactly located by contact with the flanges 60 so that there can be no variation either in the depth of the holes bored or the depth of insertion 10 of the tufts therein. This is of great importance both in the cost of the product produced and in permitting the operation of the machine at high speed. It is equally important that the holding of the brush back 15 should be rigid during the operation which is accomplished by the unyielding pressure of the cooperating wedges 61 and 64.

What I claim as my invention is:

1. In a brush machine, the combination of 20 a work carrier, a series of work holders mounted on said carrier adapted for the free insertion of the brush backs therein and the free withdrawal of the brushes when completed at spaced points in the cycle, a locating 25 bearing for accurately positioning the front face of the brush back in said holder and means for rigidly clamping and holding the brush backs in said holders against said face intermediate said points.
2. In a brush machine, the combination of 30 a work carrier, and a series of work holders mounted on said carrier into which brush backs may be freely inserted and from which completed brushes may be freely withdrawn 35 at certain points in the cycle, each of said holders comprising a recessed member having a locating face against which the front face of the back bears, a follower for engaging the rear face of the brush back, and a 40 wedge for cooperating with said follower, and means located between said points in the cycle for actuating the wedges when in registration therewith to respectively clamp the brush backs and to release the same.
3. In a brush machine, the combination of 45 a work carrier, of a holder comprising a recessed member for receiving the brush back and having a locating face for contacting with the front face of said back, a floating follower within said recessed member for 50 engaging the rear face of the brush back and a wedge for actuating said follower to rigidly clamp the brush back between the same and said locating surface.
4. In a brush machine, the combination of 55 a work carrier, of a work holder comprising a recessed member for receiving a brush back provided with a locating surface for engaging the front face of said back, a floating follower in said recessed member for 60 engaging the rear face of the brush back and a wedge for engaging said follower to clamp the brush back between the same and said locating surface, the adjacent faces of 65 said wedge and follower being non-parallel.

and contacting each other between the ends of said follower to permit angular adjustment thereof.

5. In a brush machine, the combination with a work carrier, of a work holder comprising a recessed member for receiving a brush back, a locating flange on said member for contacting with the front face of the brush back, a floating follower for contacting with the rear face of said brush back, 70 a wedge for engaging said follower to clamp the brush back between the same and said flange, a finger projecting laterally from said wedge and means engageable with said finger at different points in the cycle to actuate said wedge for respectively clamping and releasing the brush back.

6. In a brush machine, the combination with a work carrier, of means for intermittently actuating the said carrier to adjust the same in one direction step-by-step, frictional driving means for actuating said carrier in a transverse direction, indexed notched bearings on said carrier, a detent guide for engaging said notched bearings to hold said carrier from movement under the friction drive while permitting step by step adjustment in the transverse direction, means for intermittently disengaging and re-engaging said detent guide to permit frictional movement of said carrier from one notch to another, and means for adjusting said guide intermediate successive disengagements to vary the positions of the carrier in 90 said step-by-step adjustments.

7. In a brush machine, the combination with a rotary work carrier, of means for intermittently actuating said carrier in an axial direction step by step, constantly operating friction means for placing a predetermined torque on said rotary carrier, indexed notched bearings on said carrier, a detent guide for engaging said notched bearings to hold said carrier from rotation while permitting the step-by-step axial adjustment, means for periodically disengaging and re-engaging said detent guide to permit frictional rotation of said carrier and adjustment thereof from one notch to another, and means for moving said guide intermediate successive disengagements to vary the positions of the carrier in the successive step-by-step adjustments thereof.

8. In a brush machine, the combination of a rotary work carrier, means for mounting the work thereon, means for intermittently actuating said carrier step by step in an axial direction, constantly operating friction means for placing a torque on said carrier, a circumferential series of indexed notched bearings on said carrier, a detent guide for engaging said notched bearing to hold said carrier against said driving torque, means for periodically disengaging and re-engaging said detent guide to permit rotation of 120 125 130

- said carrier from one notch to another, means for adjusting said detent guide intermediate successive disengagements thereof to vary the rotative position of said carrier in 5 successive step-by-step adjustments, and means for adjusting the axis of said carrier whereby the work is adjusted in three transverse planes.
9. In a brush machine, the combination of 10 a rotary work carrier, means for intermittently actuating said carrier step-by-step in an axial direction, constantly operating friction means for placing a torque on said carrier, a circumferentially extending indexed 15 notched flange on said carrier, a guide detent for successively engaging said notched bearings and extending parallel to the axis of said carrier, means for intermittently disengaging and re-engaging said guide detent 20 to permit movement of said carrier from one notch to another, and means for moving said guide detent tangentially of the carrier to change the path of said step-by-step adjustment.
- 25 10. In a brush machine, the combination of a rotary drum, a non-rotative member within said drum and carrying the same, a frame member between said non-rotative member and said drum, means on said frame 30 member permitting axial movement of said non-rotative member while restraining the same from rotary movement, a cam carrier rotatively mounted on said frame member below said drum, a stepped cam on said cam 35 carrier extending upward within said drum, means cooperating with said stepped cam for raising and lowering said non-rotative member, and a plurality of additional cams on said cam carrier for controlling other movements of said drum.
- 40 11. In a brush machine, the combination with a rotary work carrier, of a series of work holders on said drum each comprising a recessed member for receiving a brush back, 45 a locating flange on said recessed member for contacting with the front face of the brush back, a floating follower for contacting with the rear face of said brush back, a wedge for engaging said follower to clamp the brush 50 back between the same and said flange, and fluid actuated means located at spaced points in the cycle of said carrier for operating said wedge to respectively clamp and release the brush back.
- 55 12. In a brush machine, the combination with a rotary work carrier, of a series of work holders on said drum each comprising a recessed member for receiving a brush back, a locating flange on said recessed member 60 for contacting with the front face of the brush back, a floating follower for contacting with the rear face of said brush back, a wedge for engaging said follower to clamp the brush back between the same and said flange, and resiliently yieldable fluid actu- 65 ated means located at spaced points in the cycle of said carrier for operating said wedge to respectively clamp and release the brush back.
- 70 13. In a brush machine, the combination with a rotary work carrying drum, a non-rotative member within said drum for supporting the same, a frame member surrounding said non-rotative member and between the same and said drum, means on said frame member permitting the axial movement of said non-rotative member thereon while preventing a rotation thereof, a hollow post projecting upward from said non-rotative member axially of said drum, a series of work 75 holders mounted on said rotary drum into which brush backs may be freely inserted and from which completed brushes may be freely withdrawn at certain points in the cycle, clamping means for the brush backs in said holders, fluid actuated motors for operating said clamping means to clamp and release the brush backs, said motors being supported upon said hollow post and supply conduits for the fluid to said motors passing 80 through said hollow post.
- 85 14. In a brush machine, the combination of a rotary drum, a non-rotative member within said drum and carrying the same, a frame member between said non-rotative member and said drum, means on said frame member permitting axial movement of said non-rotative member while restraining the same from rotary movement, a cam carrier rotatively mounted on said frame member below 90 said drum, a stepped cam on said cam carrier extending upward within said drum, means cooperating with said stepped cam for raising and lowering said non-rotative member, a drive mechanism for rotating said cam carrier, mechanism timed therewith for nonpositively rotating said drum, means for arresting movement of said drum, and a cam on said cam carrier for controlling said arresting means to produce a step-by-step rotative 95 adjustment of said drum.
- 100 15. In a brush machine, the combination of a rotary drum, a non-rotative member within said drum and carrying the same, a frame member between said non-rotative member and said drum, means on said frame member permitting axial movement of said non-rotative member while restraining the same from rotary movement, a cam carrier rotatively mounted on said frame member below 105 said drum, a stepped cam on said cam carrier extending upward within said drum, means cooperating with said stepped cam for raising and lowering said non-rotative member, a plurality of additional cams on said cam carrier including a cam controlling said arresting means, and a cam controlling movement of said frame member.
- 110 16. In a brush machine, the combination of a rotary drum, a non-rotative member within 115

said drum and carrying the same, an annular frame member between said non-rotative member and said drum, a stationary frame member on which said annular frame member is mounted for movement in a direction transverse to the axis of said drum, a cam carrier rotatively mounted on said annular frame member, a stepped cam on said cam carrier extending upward within said drum, means cooperating with said stepped cam for raising and lowering said non-rotative member, a second cam on said cam carrier, means cooperating with said second cam for moving said annular frame and members carried thereby upon said stationary frame member and means for intermittently rotating said drum whereby the latter is movable in three planes respectively transverse to each other.

In testimony whereof I affix my signature.
